GUSTAV BÖLLERT, OF HAMBURG, GERMANY

SPLASH CATCHER

Application filed May 13, 1929. Serial No. 362,686.

The invention here described relates to a mud-catcher capable of being attached to the footwear and intended to prevent the lower garments from getting soiled. Previous appliances intended to serve the same purpose had to be fastened to the boots or shoes by a complicated method using clasps, belts, cords, etc. Their application was unhandy; and they were difficult to clean. Apart from this, they spoilt the appearance of the boots or shoes, and for all these reasons they failed to be generally adopted.

The essential feature of the present invention is that all fastening mechanisms are wanting, and that the mud-catcher consists of a plate made of rubber or some other elastic material, fitted with an opening through which the heel is passed when the mud-catcher is to be worn. By means of insets in the rubber plate or by means of giving a special shape the mud-catcher is caused to assume an umbrella-like shape when worn. This shape (i. e., that of an inverted umbrella) is retained, and the mud-catcher closely adheres to the heel of the boot or shoe. If, moreover, a suitable color is chosen, its presence is scarcely noticeable, even when worn, so that there is no need to take it off. Moreover, this arrangement ensures easy cleaning, both when the mud-catcher is worn or not.

The accompanying drawing represents an example of applying the invention.

Fig. 1 is a plan view of the mud catcher.

Fig. 2 is a similar view with the upper plate removed.

Fig. 3 is a section of the mud catcher.

The mud-catcher consists, as shown in Figs. 1 and 2, of two plates (*a1*) and (*a2*), each of which has an opening—(*b1*) and (*b2*) respectively—near its edge. A wire inset (*c*) is inserted between the two plates, and the latter are glued together or vulcanized as shown in Fig. 2. It is advisable to punch the openings (*b1*) and (*b2*) after the two plates have been stuck together. If such a combined plate, by means of the oval openings (*b1*) and (*b2*), is passed over the heel of the shoe, the outward part of the plate assumes the shape of an open umbrella; be-

cause the opening in the plate, owing to its smaller diameter and to the tension effected by the cross section of the heel (which is wider than it), is widened out a certain distance. The plate itself is then subjected to such an amount of tension that its center presses against the heel, whilst its edge tilts downward. By means of the wire inset (*c*) it is possible to change the downward tilt into an upward tilt, even when the appliance is worn. This shape is then retained and the appliance closely adheres to the heel of the shoe. In this way it is possible to effect the easy cleaning of the whole mechanism, and—if it is found desirable to leave it attached to the heel for some reason or other instead of removing it—to tilt it upward in such a manner that, provided a suitable color is chosen, it is almost invisible.

What I claim to be new is:

A splash-catcher for shoes comprising a rubber plate having an opening slightly smaller than the cross section of the heel to which it is to be applied, a second similar rubber plate having a similar hole therein secured on the first plate, and a wire inset interposed between the plates to retain their outwardly extending splash protecting portions in a set position and to give these portions the required rigidity.

In testimony whereof I affix my signature.

GUST. BÖLLERT.
